UNITED STATES PATENT OFFICE

CHARLES F. LEMCKE, OF MILWAUKEE, WISCONSIN, ASSIGNEE OF ONE-HALF TO JOHN
A. JOHNSON, OF MILWAUKEE, WISCONSIN

STRAP BUCKLE

Application filed February 5, 1930. Serial No. 426,042.

This invention relates to improvements in strap buckles.

One of the objects of my invention is the provision of an improved type of buckle particularly adapted for use on supporting straps on clothing and straps similar to that type which are used on overalls with the bottom engaging loop connected with the buckle so that this loop can be quickly and readily adjusted along the supporting strap, and the buckle is so constructed that it can be quickly and easily attached or detached, and when in an applied position will securely grip the material of which the strap is formed so as to reduce the chances of the slipping of the buckle on the strap.

Another object of my invention is the provision of a hinged type of buckle whereby the parts may be quickly and readily supported to permit the removal of the buckle from a strap to which the same is attached and is provided with means whereby the buckle will be securely held against movement relative to the strap when the same is applied in clamping position to the strap.

With the above and other objects in view, the invention consists in the novel features of construction, the combination and arrangement of parts hereinafter more fully set forth, pointed out in the claim and shown in the accompanying drawings wherein:

Figure 1 is a top plan view of a buckle constructed in accordance with my invention;

Figure 1 is a bottom plan view;

Figure 3 is a longitudinal section taken on the line 3—3 of Figure 1; and

Figure 4 is a transverse section on the line 4—4 of Figure 1.

In the construction of my improved buckle, I provide a frame 1 rectangular in form, as illustrated, and which is constructed of a single piece of comparatively heavy wire and mounted upon this frame 1, is the base plate 2 of my improved buckle. The base plate is formed of sheet metal of suitable width and length with its longitudinal sides rolled around the longitudinal sides of the frame 1, as indicated at 3, thus securely fastening plate 2 to the frame. The base

plate 2 is provided with a plurality of punched out places 4 which form a plurality of penetrating points 5 upon the clamping face of the plate, said penetrating points being adapted to engage the material of a strap or other member to which the buckle is applied, so that when the base plate is clamped to the strap, the points or prongs will prevent slipping of the buckle on the strap.

In order to securely clamp the base plate 2 to a strap or the like, I provide a clamping plate 6, one end of which is provided with a tongue adapted to have its outer extremity provided with a loop 7 which embraces one end of the frame 1, as shown in Figure 3, to hingedly connect the clamping plate 6 to the frame.

The tongue which is provided at one end of the plate 6 extends laterally of the plate, as shown at 8, thus providing, when the buckle is clamped to a strap, suitable space for the reception of the strap between the two buckle members.

The end of the clamping plate 6 opposite its hinge point is provided with a longitudinal extending tongue having an outwardly curved portion 9 at its outer end to form a retaining shoulder. Pivotally mounted upon the end of the frame 1 opposite the sleeve 7 is a U-shaped clamping member 10, the ends of which are provided with eyes 11 adapted to be loosely mounted upon the end of the frame 1, while the intermediate portion thereon is so arranged as to screw upwardly over the arcuate portion 9 on the tongue of the clamping plate 6 and engaged behind this arcuate portion for retaining the plates 2 and 6 in relative clamping position.

Whenever the buckle or clamping device is used in connection with the supporting straps of overalls and the like, a loop engaging member 12 is provided, the ends of which are loosely mounted upon one of the side portions of the frame, as shown in Figures 1 and 2, so that the button engaging loop 12 can be readily moved to various positions for engaging a supporting button or the like.

The clamping plate 6 is provided with a

plurality of punched out places 13 forming a number of penetrating prongs 14 which are arranged in opposed relation with the prongs 5 on the base plate 2.

5 In punching out the openings 14 and 13 in the two opposed plates, it is preferred to have the openings in one of the plates arranged in spaced parallel relation as shown in Figure 2, which in the present instance 10 represents the bottom or base plate 2, while a single longitudinal line of openings is punched out in the clamping plate at approximately the central portion of the plate so that the prongs 14 will be arranged between the prongs 5, thus providing a greater 15 clamping surface than if the prongs were punched out of only one plate, as is usually the case with buckles in this type.

In the attaching of this buckle to fabric 20 straps or the like, the intermediate portion of the U-shaped member 10 is disengaged from the tongue at one end of the clamping plate and the clamping plate swung outwardly to permit the positioning of the strap between the base plate and the clamping plate. The 25 clamping plate 6 is then urged downwardly toward the base plate until the U-shaped clamping member 10 can be moved upwardly over the arcuate portion 9 of the tongue of the clamping plate and in this manner, it 30 will be noted that the prongs 5 and 14 will be urged into penetrating position relative to the strap to which the buckle is applied, so as to securely hold the buckle in position 35 and prevent any sliding movement of the buckle on the strap.

While I have shown and described the body 40 engaging loops 12 as applied to the frame of the buckle, it will be apparent that various other types of supporting elements may be used in connection with my improved buckle and the buckle in itself is of such construction that it can be manufactured at a very low cost 45 and the effective operation of the device is such that a strap of almost any material can be securely clamped between the two members 2 and 6, so that the penetrating prongs 5 and 4 will prevent any sliding movement 50 of the buckle on the strap.

60 While I have shown and described the preferred embodiment of my invention, it will be apparent that slight changes may be made in the construction when putting the invention into practice without departing from 65 the spirit of the same or the scope of the appended claim.

I claim:

60 In a buckle of the class described, a substantially rectangular frame, a base plate having its longitudinal edges embracing the sides of the frame, penetrating lugs carried by the base plate and extending at one side thereof, a clamping plate pivotally connected at one end to one end of the frame, penetrating lugs carried by the clamping plate

and adapted to be arranged in opposed relation with the lugs on the base plate, and a movable retaining member carried by the frame and adapted to be engaged with the end of the clamping plate opposite its pivot point for retaining said clamping plate in clamping position relative to the base plate.

In testimony that I claim the foregoing I have hereunto set my hand at Milwaukee, in the county of Milwaukee and State of Wisconsin.

CHARLES F. LEMCKE.
